UNITED STATES PATENT OFFICE.

INEZ GRAVES, OF SEATTLE, WASHINGTON.

IRONING-BOARD.

1,352,259.

Specification of Letters Patent.

Patented Sept. 7, 1920.

Application filed May 2, 1919. Serial No. 294,349.

To all whom it may concern:

Be it known that I, INEZ GRAVES, citizen of the United States, residing at Seattle, in the county of King and State of Washington, 5 have invented new and useful Improvements in Ironing-Boards, of which the following is a specification.

The object of the invention is to provide in combination with an ironing board an appropriate stand therefor, the stand comprising a leg or support element hingedly attached to the board and operatively connected with a clamping member also attached to the board but designed to effect a grip 15 upon the edge of a table or shelf, so that the latter acts as one support of the board while the leg or support member acts as the other. The leg member referred to is adapted for folding down against the board when not in 20 use and when thus folded relieves the clamping member so that the grip exerted by the latter is released. Thus the board when not in use may be placed in a cupboard out of the way where it does not take up much room 25 because of parts connected therewith lying close to the board when in inoperative position.

The further object of the invention is to provide a sleeve board which is mounted on 30 the main board in such a way that it may be readily detached therefrom or swung to a position where it is out of the way when the main board is in use.

A still further object is to provide in a 35 device of this character a construction which is simple in design, durable and effective in operation and inexpensive to manufacture.

Other further objects appear in the following description wherein the invention is 40 set forth in detail. To the exact construction in which it is shown and described the invention is not to be restricted. The right is reserved to make such changes or alteration as the actual reduction to practice may suggest, in so far as such changes or alterations are compatible in spirit with the annexed 45 claim.

In the accompanying drawings:

Figure 1 is a centrally longitudinal sectional view of the invention.

Fig. 2 is a bottom plan view of the improved board.

Fig. 3 is a section on the line 4—4 of Fig. 2.

Referring to the drawings, the invention 55 is shown as being clamped to the top of a table 1. It comprises the main board 2, the

supplemental board or bosom and sleeve board 3 and appropriate means by which the main board can be clamped to the table 1 at one end and supported at an intermediate 60 point between the table and the other end.

On the bottom of the main board 2 there is attached a cross bar 4 which is recessed on the end face as at 5, the bottoms of the recesses being slightly inclined in the direction 65 of the rear end of the board. Clamping plates 6 are secured to the cross bar 4 and lie in the recesses 5, being secured to bar 4 and to the board by means of bolts 7 which receive wing nuts on their lower ends, the wing nuts 70 abutting the bottom faces of the clamping plates 6. The bolts 7 pass through the clamp plates and the holes through which they pass are obviously of such a diameter that a slight rocking movement will be permitted 75 the clamp plates, the forward extremities of which are adapted for clamp engagement of the under face with the top of the table 1 adjacent the edge, the forward end of the board lying on the top of the table when the 80 plates 6 engage the top.

Except when the rear ends of the plates 6 are depressed, a firm clamp engagement of the plates with the table top is not possible, the inclined bottoms of the recesses 5 permitting 85 the rear ends of the clamp plates to incline forward and thus relieve the forward ends of these plates from clamp engagement with the table top. Means is provided, however,

for depressing the rear ends of the 90 clamp plates, the two of which are interconnected by a cross bar 9 adjacent their rear ends. The means referred to comprises a leg 10 having a cross bar 11 attached to the upper end thereof and this leg and its cross 95 bar are mounted on the board 2 on the under face thereof, a hinge 12 effecting this attachment of the leg and its attendant cross bar to the board. The hinge is so mounted that the leg may swing to a vertical position with 100 reference to the board when the upper edge of the cross bar abuts the under face of the board. The leg is thus precluded from movement beyond this position but may be swung back against the board when its lower 105 end rises adjacent the rear end of the board.

In swinging the leg in the vertical position referred to, the cross bar 12 is brought into contact with the upper faces of the rear ends of the plates 6, thereby depressing 110 them, since the width of the cross bar 11 is greater than the thickness thereof. Hence

a clamping engagement with the top of the table 1 is effected if the board had previously been laid on top of the table to permit the forward ends of the clamp plates 5 to lie beneath the top.

The rear ends of the clamp plates when not engaged by the cross bar 11 are intended to be held as close to the under face of the board 2 as possible, so as to provide as wide 10 a space as possible between the forward ends of the plates and the under face of the board for the purpose of having the device readily engage the edge of the table initially. To this end a spring 13 is employed, this spring having one end secured to a preferably wide member 14 which is connected to the two plates 6, as shown. The remaining end of this spring connects 15 with wire strand 15 formed with an eye at each end with one of which the end of the spring 14 connects, the other end serving as 20 the means for securing the strand to the under face of the board by means of a screw or other fastening device 16. The strand 15 is attached to the board between the cross 25 bar 11 and the rear end of the board but it extends to the forward of the cross bar and above the latter to receive the end of the spring 13. The movement of the leg 10 30 then to a perpendicular position with reference to the board serves to clamp the strand between the cross bar 11 and the board and in so doing throws the end of the spring closer to the board, thereby increasing the 35 tension on the spring. Thus when the leg 10 is folded down against the board, the point of connection between the spring and the strand may more nearly align itself with the point of connection between the spring 40 and the member 14 and the point of connection between the strand and the board when the tension on the spring is obviously reduced. This arrangement makes for the reduction of the tiring effect on the spring, 45 thus serving to keep it active and to increase its tension when the leg 10 is turned down, when the increased tension causes the rear ends of the plates 6 to effectively and firmly

clamp the cross bar 11 and to hold it in a position where it retains the leg 10 in vertical position.

The sleeve board 3 is carried by a Z-shaped arm 17, one extremity of which is threaded to receive a wing nut 18, this threaded portion of the Z-shaped member passing through 55 an appropriate hole formed in the board 2, the Z-shaped member lying against the board 2 on the upper face and the wing nut abutting the board 2 on the bottom face. This sleeve board may readily be removed from 60 the main board if desired by detaching the wing nut 18 and may be moved out of the way even when attached to the board 2, it being swung around on the threaded portion as a pivot to a position where it practically 65 leaves the main board 2 free for use.

From foregoing description and the accompanying drawings it is believed that a clear enough understanding of the invention is to be had to render further description of the invention unnecessary.

The invention having been described, what is claimed as new and useful is:

A household article of the kind described comprising a board, a pair of clamping plates mounted on the under face of the board so that their one extremity may in conjunction with the board effect a clamping operation upon the edge of a shelf or a table, a leg, formed with a cross bar which is 75 hingedly attached to the board on the under face thereof and which lies between the other extremities of the plates and the board, the leg limited to a substantially perpendicular position with reference to the 80 board but foldable down thereagainst, the cross bar bearing against the plates, a spring having one end connected with the plates, and a wire strand passing between the cross 85 bar and the board and having one end secured to the spring and the other end to the board in the manner and for the purpose 90 herein specified.

In testimony whereof I affix my signature.

INEZ GRAVES.
